UNITED STATES PATENT OFFICE.

CHESTER COMSTOCK, OF NEW YORK, N. Y., ASSIGNOR OF ONE-HALF TO CHARLES LEFFLER, OF BROOKLYN, NEW YORK.

BALANCED CENTRIFUGAL PUMP.

1,085,020.

Specification of Letters Patent.

Patented Jan. 20, 1914.

Application filed August 30, 1911, Serial No. 646,814. Renewed August 14, 1913. Serial No. 784,791.

To all whom it may concern:

Be it known that I, CHESTER Comstock, a citizen of the United States, residing in New York city, in the county of Kings and State of New York, have invented certain new and useful Improvements in Balanced Centrifugal Pumps, of which the following is a specification.

My present invention relates to an improvement in centrifugal pumps, but more especially to a rearrangement of the impeller units, such as are described and claimed in my concurrently pending application, Serial No. 621,969, filed April 19, 1911, wherein a series of peculiarly designed and operating impelling unit members are shown arranged in series, all of said impeller units propelling fluid in one direction from the inlet to the exhaust ports. In my present improvement I have rearranged these same impeller units in a new manner in order to increase the efficiency of the pump, as a whole, by decreasing the internal friction caused by the end thrust, thereby reducing the wear of the parts. I have discovered that if the impeller members of a centrifugal pump are caused to rotate in certain well defined positions in relation to the stationary or co-acting parts, greatly increased efficiency may be obtained. I have also found that to rely entirely for this steadiness of position upon an automatic balancing of the pressure on the sides of the impellers, does not, owing to the varying conditions of suction and discharge, always produce the desired results, and the effect is a reduced efficiency and an undesirable wearing of the parts which sustain the end thrust, caused by this unbalanced condition, while on the other hand it is not desirable to carry the entire load of the pump by thrust bearings, for various well-known reasons.

The object of this invention is to maintain the impellers in their most advantageous position for efficient service, with the smallest amount of friction and wear on the parts which must come in contact, in securing this steadiness of position.

The above results are accomplished in part, automatically, by arranging the impellers in opposition to one another. By this is meant that one of the impellers with its co-acting guide blades is reversed as relates to the direction of its discharge, where-

55 by the force of the discharge of this reversed

pump unit is caused to counteract the force of the discharge of the other pump units as relates to the end thrust of the shaft, and, by providing a balancing chamber for each impeller a partial balancing effect is secured for that impeller by means of the leakage, which is incidental to the construction and operation of the pump. A further balancing provision is made by means of a connecting passage from the balancing chamber of the reversed impeller to one or more of the balancing chambers in the preceding series. This automatic operation will be more fully described hereinafter.

A further improvement in this device is in the use of a manually adjustable valve controlling means, whereby I am enabled to adjustably direct and maintain the fluid pressures so that a pressure from high pressure chamber, such as the discharge chamber, is admitted to a low pressure balancing chamber through a valve-controlled port to any desired amount, to the limit of said high pressure, thereby obtaining a regulating means for balancing the impeller units, said regulating means being variable at will.

A further advantage of my device is, that owing to the construction and arrangement of the impeller units, the fluid is progressively energized by each of the impeller units in the series through which the said fluid passes from inlet to exhaust, and at the same time one of the impeller units is in opposition to the impeller units preceding in the series. In other words, while each of the successive impellers add pressure to the fluid, progressively, one of the same series of successively arranged impeller units is adapted to discharge the fluid in opposition to that of the other members of its series as relates to the end thrust of the shaft, thereby obtaining a further balancing by reason of said reverse discharge.

It will be seen that throughout my description I have referred to the separate impellers and their fixed disks as pump units, said pump units being literally an assemblage of parts arranged to receive the fluid, supply force thereto, and discharge the same, and it is for the purpose of distinguishing this construction or assemblage from that as indicated by the expression "impeller units" or "impeller members," which constitute one of the parts of the said pump units that I make use of the above noted expressions.

In connection with the above described means for securing the minimum amount of end thrust on the shaft and in order to secure the rotating parts in that fixed position relative to the stationary and co-acting parts of each, which will give the greatest efficiency to the pump, I provide a thrust bearing for the shaft, located in a chamber where means for lubrication is provided. This thrust bearing, owing to the balancing of pressure on the opposite sides of the impellers as above mentioned, is enabled to maintain the impellers in the before mentioned well defined positions with the smallest amount of friction and wear.

While in the present instance I provide an end thrust bearing on the main driving shaft of said pump, and which is shown as the conventional type of ball thrust bearing, any practical type of thrust bearing which will perform the required work in a satisfactory manner will answer the purpose for which I have adapted the same. This bearing is for the purpose of obtaining the before mentioned steadiness of position of the impeller members and is intended to rigidly maintain the impeller members in fixed rotative planes in relation to their co-acting parts, that is, the fixed directing disk members against which they may come in rotating contact, and by reason of the said thrust bearing this contact need not be absolute but may be set to the smallest amount of clearance consistent to the reduction of friction and wear.

In the accompanying drawings Figure 1 is a sectional view of my improved centrifugal pump. Fig. 2 is a section taken on line 2-2, Fig. 1, looking in the direction of the arrows. Fig. 3 is a section taken on line 3-3, Fig. 1, looking in the direction of the arrow. Fig. 4 is a rear view of an impeller member. Fig. 5 is a section of the same taken on line 4-4, Fig. 4. Fig. 6 is a sectional view of the opposing or balancing member of a similar form to that shown in Fig. 4. Fig. 7 is a front view of one of the fixed directing disks. Fig. 8 is a section taken on line 7-7, Fig. 7. Fig. 9 is a fixed directing disk for the reversed or balancing impeller member 9.

In Fig. 4 is shown one of the impeller members, the construction of all of which in this pump are similar. The impeller members are shown as having only three wing members 50, 51, and 52, but a different number may be used.

I have found it desirable in practice to provide a number of intermediate series of short wing members 53, placed intermediate of the main wing members 50, 51, and 52. These intermediate members are comparatively short and only bridge the opening 54 and further, are for the purpose of aiding the main members 50, 51, and 52 in presenting the fluid for the action of the guiding

blades 65 on the fixed fluid directing disks 66. The impeller 4 receives the fluid at a point 55 near the center, and the fluid entering the interior of said impeller passes outwardly between the impeller wings 50, 51, and 52, as indicated by the arrow line 56, and is then carried sidewise as indicated by arrow 57 until it reaches the discharge point, as at 58 where the discharge is directed toward the axis of the impeller shaft. For the purpose of centrally directing this discharge, the overhanging portion of the impeller 59 is so arranged that the discharge opening 58, lies between the inner edge of the wall 60 and the outer edge of the wall 61. A circular wall 62 is formed at the edge of the impeller members 50, 51, and 52, thus preventing the fluid from escaping in a direct line and causing it to go in the direction of the before mentioned arrow 57.

In Figs. 4 and 5 is shown a hub 63, said hub forming one wall of the annular inlet passage 51, and integral with the wall 62, and having a key-way 64 therein for the purpose of keying the same upon the driving shaft.

In Fig. 6 is shown a reversed impeller member having a reversely extending hub 75 wherein the fluid is taken in at the annular inlet port 76 and going in the direction 95 of the arrows 77 discharges from an overhanging port 78, similar in construction to the port 54 in Fig. 5. It will be noted that in Fig. 5 the fluid crosses the face of the blades 50, 51, and 52 from the rearwardly located central port to the outer located peripheral port, thus making a transit diagonally across the face of the impeller blades 50, 51 and 52, whereas in the impeller members shown in Fig. 6, the fluid enters at the central inner port and is discharged from the outer port 78, both the inlet and outlet being on the same side of the impeller.

In Fig. 7 the fluid directing guides 65, which are integral with a fixed disk 66, receives the fluid from the overhanging discharge port 54 of the impeller member 4 and directs it toward the central inlet port 67, it being there received and taken up by the next impeller member.

In Fig. 8 is shown a sectional view of the fixed disk member 66, Fig. 7, the portion in full lines indicating the type of disk member which would be utilized with impeller member 4, whereas the dotted cylindrical portion 68 indicates the extension that would be necessary to receive and direct the fluid from the impeller member 4 into the reversed impeller member 6. This may be seen by referring to Fig. 1. In Fig. 9 is shown a similar fixed disk member with its fluid directing guide 69 thereon, the only difference in this member over that of the previous mentioned being in the opposite direction in which the said fluid guides 69 are arranged. It is ob-

vious that if the impeller members are constructed alike as to their impeller wings, that when they are faced against one another upon a shaft rotating in one direction that the fluid guides would have to be reversed to properly receive and direct the flowing fluid.

In Fig. 1 the fluid enters the inlet port and flowing in the direction of the arrows 2 through the inlet port 3 enters the first impeller member 4, and flowing in the direction of the arrows 5 enters the oppositely placed peripheral discharge port 6. The fluid is therupon received by the fluid directing guides 7 which are a part of the fixed disk 8 and is thus caused to be axially discharged toward the center of the next impeller member 4', as indicated by the arrows 9. This cycle is repeated in the next impeller member and is again received by a fixed fluid directing disk 10 of the type indicated in Fig. 8, with its extended cylindrical extension 68. The fluid then takes the course indicated by arrows 11 through the central port 12 formed between the hub 75 and the cylindrical extension 68 of the impeller member 14 (which impeller member is of the same type as that shown in Fig. 6 with its reversed hub 75, the fluid being directed in the manner described for Fig. 6), and it is therupon received by the directing guides 15 which are arranged upon the fixed disk 16 and taking the course of the arrows 17 it passes through the discharge port 18.

At points 19, 20, and 21, Fig. 1, are shown surfaces where the rotating impeller members 4, 4', and 14 are in rotative engagement with the fixed disk members 8, 10, and 16, a certain amount of leakage of the fluid pressure takes place and enters the chambers 22, 23, and 24, formed at the outside of the said impeller members and at one side thereof. A series of separating ring members 25, 26, and 27, are placed between the ends of the pump caps 28 and 29 and between the fixed disk members 8, 10, and 16, for the purpose of maintaining a fixed predetermined spacing therebetween and form thereby what I call balancing chambers.

The automatic balancing feature previously mentioned is partly caused by the seepage or leakage of fluid pressure by the joints 19, 20, and 21, into the chambers 22, 23, and 24, before mentioned, thus causing pressure to be accumulated in the said chambers. During the operation of this pump I have found that if the first impeller member gives a pressure of about 10 pounds, the second impeller would give a pressure of about 20 pounds, and so *ad lib.*, and it is due to the fact of this increase of pressure in the succeeding impellers that I am enabled to equalize the pressure throughout, for instance in the chamber 22 of the impeller 4 the pressure therein due to the leakage from impeller 4, would be about 7 pounds and con-

versely, in chamber 23 the pressure would be about 15 pounds, due to the pressure in impeller member 4', and in chamber 24 of the impeller member 14 the pressure therein would be about 26 pounds.

The method by which I obtain a balance on the impelling members and thereby relieve the thrust bearing of all undue strain except that of keeping the impellers in their proper rotative place is as follows: The pressure in chamber 22 of the impeller 4 and in chamber 23 of the impeller 4', tends to offset the pressure in chamber 24 of the impeller 14. The pressure in said chamber in the space adjacent to the periphery of the impellers can be neglected entirely because the pressure there generated is between the inner wall of the supporter rings 25, 26, and 27, and the said peripheries and therefore neither adds to nor subtracts from the end-thrust on the shaft 39. The back walls A—A of impellers 4 and 4', and the back wall 79 of the impeller 14, are the areas effected by the pressure in said chambers. It is furthermore to be understood that the pressure in these chambers is somewhat less than that generated in their respective impellers, as has been previously noted. It will further be noted that the area presented by these back walls A—A and 79 also vary somewhat.

For the purpose of bringing out the arrangement of pressure whereby I obtain the aforesaid balancing I will introduce a few figures. It will be understood that these figures are only approximate but are entirely in proportion to those that I have found in practice. If, as was previously stated, the pressure generated in the first impeller is 10 pounds, that in the second about 20 pounds, and that in the third chamber about 30 pounds, then the pressure in the chambers 22, 23, and 24, would be about 7, 15, and 26 pounds per square inch, respectively. Taking a square inch of area of the pressure sides A—A and 79, neglecting for the moment the actual areas of the impeller members, which are nearly equal, we would then have a combined pressure per square inch on the side walls A of the impellers 4 and 4' of 22 pounds, and on the wall 79 of the impeller member 14, a pressure of 26 pounds per square inch, thus leaving a difference of 4 pounds pressure in favor of the impeller member 14. For the purpose of further off-setting this extra pressure of the impeller member 14, I connect the passageway 30 in the side wall of the housing 1' from the impeller member 14 to the impeller member 4 by means of two ports 31 and 32. As above stated, the pressure in chamber 22 of the impeller member 4 would be about 7 pounds and that in the chamber 24 of the impeller member 14, 26 pounds, the difference therebetween being 19 pounds in favor

of chamber 24. By permitting this excess fluid pressure from chamber member 24 to enter the chamber 22, a further balancing effect is obtained, the pressure in the two 5 chambers becoming very nearly equal. Still further pressure is to be considered, namely, the pressure in the chambers formed by the fluid guides on the fixed disk members 8, 10, and 16, on one side and by the side walls of 10 the impellers opposite. It is evident that, the disks being immovably fixed and the rotating impeller members being fixedly attached to the main shaft, the unit pressure then tends to force the impeller members 4 and 4' to the left hand and the impeller 15 member 14 toward the right hand.

There is a further discrepancy of areas in the walls 62 of the impeller members 4 and 4' and the wall 81 of the impeller member 20 14. This discrepancy requires a further adjusting to cause a balance on the different impeller members. To obtain this further refinement and to permit of variable adjustment of this pressure to meet the varying 25 conditions under which such a pump may operate, such as differences in lift, suction lift and differences in pressure or head, I arrange a port 34 which connects the pressure chamber 23 of the impeller member 4' with the exhaust chamber 18', the pressure in said chamber being equal to that of the last impeller 14' and consequently is greater than that in the chamber 23, so by adjusting the valve member 35 which controls the port 30 34 and the set-screw 37 which controls the port 36, higher pressure from the chamber 18' is adjustably regulated and permitted to enter chamber 23, thereby causing a further pressure toward the right hand side of 35 the pump. I have found in practice that I am enabled by this valve arrangement to over-come a left hand thrust that would be natural in a pump of the herein disclosed construction and cause the pressure to be 40 come an opposing one, or I can maintain it in a right hand direction if so desired.

It will be seen by the foregoing that I can meet and maintain automatically any condition of balancing that may be met 45 50 with in any pump of a given capacity, and that I am enabled, by my present construction, to cause the internal forces, which may naturally operate to cause an over-balance in one direction as regards the direction of 55 end thrust, to be created in an opposite direction to a balance, or in excess.

Various methods have been adopted heretofore for the purpose of securing a minimum of end thrust on the shaft of centrifugal pumps, but these methods have differed widely from that shown in the present application, as will be seen from the following statement.

Two kinds of impellers have been in use 60 65 in multi-stage centrifugal pumps, one type

of impeller being arranged to discharge radially outward, that is, outward at right angles to the axis of the impeller. In impellers of this type the discharge cannot possibly have any direct influence upon the 70 end thrust of the shaft which is rotatably mounted at right angles thereto. The other type of impeller is one arranged to discharge axially, that is, in a direction parallel to the axis of the impeller and its shaft. In this 75 type of impeller the discharge has a positive and direct influence upon the end thrust of the shaft, the said influence being exerted upon an area of the impeller equal to the area of its discharge port.

From the above noted statements it will be seen that the first noted impeller has an indirect influence as relates to the end thrust of a shaft, and the second noted impeller has a direct influence as relates to the end thrust 80 of a shaft, and therefore to distinguish one from the other one may be termed "indirect", to distinguish it from the other, the said indirect influence being caused by fluid pressure accumulating on each side of the 85 impeller, due to leakage at the point where the edge of the impeller near its discharge port is adjacent to other co-operating parts. This indirect pressure on the sides of the impeller is equal per square inch of area on all 90 the area subjected to it, but the area affected is greater on one side than on the other.

If the impellers discharge radially outward, the end thrust is caused by suction and pressure of equal pounds per inch on all opposing sides of impellers of unequal area. If the impellers discharge axially the end thrust is caused by suction. In a pump having an axial discharge a balance more or less perfect has been secured by having 100 two series of pump units on the same shaft, one of the series being opposed to the other in the direction of discharge, each series having an independent suction pipe, one at either end of the pump case and discharging 105 into a volute chamber surrounding the two central impellers of the series, the flow of the central impellers being radially outward in the volute discharge chamber.

In a pump of the radially outward discharge type, the passageways from the discharge port of one impeller and the inlet port is first outward, then axial, and then inward toward the center of the pump, and the above is true whether the impellers are 115 arranged in pairs opposed to one another, or in any other relative position. The said passageway is necessarily long, circuitous, and of a thin cross section, presenting a large amount of surface to the volume of 120 flowing water, causing a large amount of skin friction and a corresponding loss of efficiency in the pump. In neither case can there be any re-acting effect on the said impeller as the discharge leaves the pump unit 125 130.

and flowing toward the outer port of the pump unit is in a fixed partition that has a portion which separates the outlet port from the chamber in which the impeller revolves,

5 and also the pressure at the outlet port side of the pump unit is less than at the point of discharge of the impeller, and of about equal pressure to that in the chambers at the side of the impeller.

10 In the present noted construction the passages from the outlet of one impeller to the inlet of the succeeding impeller is direct with the smallest amount of obstruction to velocity of the fluid moving therein, and 15 forms the shortest possible route in which the flow may be directed, and is of such cross sectional area that a minimum amount of skin friction is presented to the moving volume of water. Hence the skin friction of 20 the passages is less and the efficiency of the pump is greatly increased.

The above noted construction and arrangement of parts while contributing largely to the efficiency of the pump, also provides a 25 simple and effective method of eliminating the end thrust on the impeller shaft and the detrimental consequences thereof. The full force of the direct pressure of discharge and the re-acting effect as it leaves the pump 30 unit, comes upon the discharge port side of the impeller. The opposite side of the impeller and this alone receives the indirect influence of the discharge due to leakage between the impeller near its discharge port 35 and the parts next adjacent thereto. This leakage collects in the chamber arranged in the pump unit on the side of the impeller opposite to the discharge port side, and to the extent of the pressure in this chamber 40 the said pressure becomes a balancing force to the pressure on the discharge port side.

The reversal of the last pump unit of the series, as relates to the direction of the flow of its discharge, provides a ready means of 45 completely balancing the pump whereby the pressure in the last balancing chamber of the series is transferred to the first balancing chamber in the same series, or to the other impeller balancing chambers if so desired.

50 The reversal of the last pump unit of the series also provides a natural space for the discharge chamber between the last pump units of the series.

55 Having thus described my invention, I claim:

1. In a centrifugal pump, a series of pump units in each of which is an impeller whose discharge port is located near the periphery 60 of the said impeller and facing to discharge radially inward, the said series of pump units being arranged to progressively energize fluid from inlet to exhaust and having the last unit of the series reversed, the discharge port of the impeller in this reversed

unit being located in that side wall of the impeller which is nearest to the preceding unit.

2. In a centrifugal pump comprised of a housing having an inlet port, a plurality of impeller members rotating in said housing, one of the said impeller members discharging in an opposing direction to all the other impeller members, through a discharge port in the impeller located in one of the side walls of the impeller and near the periphery thereof, into a ring-shaped chamber connected with the discharge port of the pump. 70

3. In a centrifugal pump comprised of a housing having an inlet port, a plurality of impeller members rotating in said housing, one of the said impeller members discharging in an opposing direction to all the other impeller members through a discharge port in the impeller located in one of the side walls of the impeller and near the periphery thereof, into a ring-shaped chamber connected with the discharge port of the pump, said ring-shaped chamber being located between the aforesaid impeller and the other impellers with which it is associated. 80

4. In a centrifugal pump, a pump unit consisting of an impeller whose discharge port is located in one side wall of the said impeller and near the periphery thereof, a stationary disk having guide blocks thereon to direct the flow to a centrally located outlet port in the disk, and a balancing chamber located at the side of the impeller that is opposite to that in which the discharge port is located. 90

5. In a centrifugal pump, the combination of two pump units which are opposingly arranged as relates to their discharge, each pump unit having a centrally located inlet port and a centrally located outlet port, an impeller fixedly mounted upon a shaft for rotation, said impeller having a centrally located inlet port and a discharge port located near the periphery thereof discharging radially inward, and guiding blades to cause a continued flow of the fluid toward the centrally located outlet port, the said outlet port of each pump unit being adjacent to the centrally located outlet port of the other pump unit. 105

6. In a centrifugal pump, the combination of a housing, a shaft suitably mounted therein for rotation, two or more impellers fixedly mounted on the shaft and fixed disks disposed intermediately of said impellers and having arranged thereon guiding blades to radially direct the flow of the transmitted fluid for each impeller, one of the said impellers with its fixed disks and guiding blades being reversed as relates to the other of said disks and as regards the direction of its discharge, whereby the pressure of the discharge of one impeller has a counteracting effect on the pressure of the discharge 110

of the other impellers as relates to the end thrust of the shaft.

7. In a centrifugal pump comprised of a housing having an inlet port, a plurality of impeller members rotating in said housing, and a plurality of stationary disks located between said impeller members forming a plurality of pump units, one of said stationary disks having a centrally located tube-like extension which forms the outlet port of one part of the unit, said tube-like extension passing through the outlet port of the next succeeding pump unit making a moving connection with the inlet port of the next succeeding impeller.

8. In a centrifugal pump, a shaft suitably mounted for rotation, having two or more impeller members fixedly mounted thereon, each of the said impeller members having a discharge port located in one side wall of the said impeller near the periphery thereof and facing to discharge radially inward, two of the said impeller members being so placed on the shaft that the discharge-port side of each impeller shall be adjacent to and facing the other impeller.

9. In a centrifugal pump, the combination of an impeller having an annular casting with end walls, a discharge port located near the periphery of the impeller, and in the outer wall of a recess formed in one of the end walls of the impeller, and an inlet port centrally located in the same end wall of the impeller.

35 10. In a centrifugal pump, the combination of a shaft suitably mounted for rotation, two or more impeller members fixedly mounted on the shaft, and a stationary disk arranged to coöperate with each impeller, each stationary disk having guiding blades thereon to guide the flow of the transmitted fluid toward the centrally located outlet port in the said disk, one of the impellers and the guiding blades associated with it being constructed and arranged to discharge in a direction opposite to the discharge of the other impellers with reference to the end thrust of the shaft.

11. In a centrifugal pump, two pump units which are opposingly arranged as relates to their discharge, each of the said pump-units having a centrally located outlet or discharge port, the said outlet port of each unit being so located that it shall be adjacent to the outlet port of the other unit, and the discharge therefrom of each shall flow toward the outlet port of the other in a direct axial line.

12. A centrifugal pump having an inlet and discharge port, and a series of pump units organized to energize fluid progressively from the inlet to the discharge port, a ring-shaped discharge chamber connecting with the discharge port of the pump, the said discharge chamber being located be-

tween two of the pump units of the series, the diametrical inner wall of the said chamber being a centrally located tube extending from one of the pump units to the other two said pump units.

13. A centrifugal pump having an inlet and discharge port, and a series of pump units organized to energize fluid progressively from the inlet to the discharge port, a ring-shaped discharge chamber connecting with the discharge port of the pump, the said discharge chamber being located between two of the pump units of the series, the diametrical inner wall of the said chamber being a centrally located tube extending from one of the pump units to the other of the two said pump units, the said tubular member forming a passageway from the outlet port of one pump unit to the inlet port of the next pump unit of the series.

14. The combination of a centrifugal pump having an inlet and discharge port, of a series of pump units organized to energize fluid progressively from the inlet to the discharge port of the pump, an impeller located in one of the said pump units and suitably mounted for rotation, the said impeller having a centrally located inlet port in that wall of the said impeller that is nearest to the preceding pump unit of the series, and an outlet port located near the periphery of the impeller and in the same wall of the said impeller as the inlet port.

15. The combination of a centrifugal pump having an inlet and a discharge port, of a discharge chamber connecting with the discharge port of the pump, and a series of pump units organized to energize fluid progressively from the inlet to the discharge port, one of the series of pump units having an outlet port centrally located in one wall of the said pump units and projecting across the discharge chamber to connect the said unit with the next succeeding unit of the series.

16. In a centrifugal pump having an inlet and a discharge port and a plurality of pump units, a ring-shaped discharge chamber connected with the discharge port and located between two of the said pump units, the side walls of the said discharge chamber being the stationary disks in which are centrally located the outlet ports of the two pump units between which the discharge chamber is located.

17. The combination of a centrifugal pump having an outlet and a discharge port, of a series of pump units organized to energize fluid progressively from the inlet to the discharge ports, and a discharge chamber connected with the discharge port and located between two of the pump units of the series, one of the series of pump units opposed to the other unit of the series as relates to the direction of flow of its dis-

- charge, the said opposed pump unit having a centrally located inlet port in the wall nearest to the preceding pump unit, and an outlet port in the wall nearest to the preceding pump unit of the series, the said outlet port discharging axially into the discharge chamber in a direction toward the last preceding pump unit of the series.
18. The combination in a centrifugal pump having an inlet and a discharge port and a series of pump units, of a discharge chamber connected with the discharge port and located between two of the pump units of the series, a pump unit located on one side of the said discharge chamber, the outlet port side of the said pump unit being toward the said chamber and having an extended portion at the outlet port to conduct the discharge of the next succeeding pump unit, and a pump unit located at the opposite side of the said chamber from the preceding unit, said last pump unit having an inlet port adapted to receive the fluid from the extended outlet port of the preceding unit and having an outlet port in the wall nearest to the said chamber, said outlet port adapted to discharge axially into the said discharge chamber.
19. The combination in a centrifugal pump having an inlet and discharge port and a discharge chamber connected with the discharge port, of two pump units that are opposingly arranged as relates to their discharge, each pump unit having an inlet and an outlet port, impellers rotatably mounted in said pump units, each impeller having a centrally located inner port, also a discharge port located near the periphery thereof, and a stationary disk having guiding blades thereon to direct the flow of the transmitted fluid toward a centrally located port in the disk, said port forming the outlet port of the pump unit, the stationary disks of the two pump units forming the side walls of the said discharge chamber.
20. In a centrifugal pump having a plurality of impellers suitably mounted for rotation, each of the said impellers having a discharge port in one side wall of the impeller and near the periphery thereof, and having a balancing chamber for each impeller, the said balancing chamber being located at the side of the impeller that is opposite to that in which the discharge port of the impeller is located, a ring-shaped discharge chamber connected with the discharge port of the pump and located between two of the impellers which are so mounted that the discharge port of each shall be in the side of the impeller nearest to the discharge chamber, and a conduit connecting the balancing chamber of one of
- the said impellers with the balancing chamber of an impeller that is located on the opposite side of the discharge chamber.
21. In a centrifugal pump having an inlet and a discharge port, a series of pump units organized to energize fluid from the inlet to the discharge port of the pump, in which each unit of the series has an impeller whose discharge port is located in one of the side walls of the impeller, and near the periphery thereof, a stationary disk having guide blades thereon to direct the flow radially inward to the centrally located outlet port of the unit, and a balancing chamber located at that side of the impeller that is opposite to the discharge port side of the impeller, the last balancing chambers of the series being opposingly arranged to all the other balancing chambers in the series with reference to its influence on the end thrust of the shaft.
22. A centrifugal pump comprised of a housing, a shaft rotatably mounted therein, a series of impeller members fixedly mounted on the said shaft for rotation therewith, each of the said impellers having a discharge port located in one of the side walls of the said impellers and near the periphery thereof, whereby the full pressure of the discharge due to the action of the impeller is exerted on the discharge port side of the impeller to cause an end thrust of the shaft, and having the last impeller of the series opposingly arranged to all the other impellers of the series with reference to its influence on the end thrust of the shaft.
23. A centrifugal pump comprised of a housing, a shaft rotatably mounted therein, a series of pump units therein, each pump unit of the series having an impeller fixedly mounted on the said rotatable shaft, each of said impellers having a discharge port located in one side wall of the impeller and near the periphery thereof, whereby the full pressure of the discharge due to the action of the impeller is exerted on the discharge port side of the impeller, a balancing chamber in each pump unit of the series located at that side of the impeller that is opposite the discharge port side of the impeller, and having one of the balancing chambers in the series opposingly arranged to the other balancing chambers of the series with reference to its influence on the end thrust of the shaft, a passage-way leading from the balancing chamber of the opposingly arranged unit to one or more of the balancing chambers in the other units of the series.
